WATCH BRACELET OR SIMILAR ARTICLE

Yuen Sang Poon, Hong Kong, assignor to Baldwin Bracelet Corporation, New York, N.Y., a corporation of New York

Filed June 12, 1968, Ser. No. 12,317

Term of patent 14 years

Int. Cl. D11—01

U.S. Cl. D45—4

FIG. 1.

FIG. 2.

FIG. 3.

FIG. 4.

FIG. 5.

FIG. 6.

FIG. 7.

FIG. 8.

FIG. 9.

FIG. 1 is a top plan view of a watch bracelet showing my new design;

FIG. 2 is an enlarged top plan view of the two links indicated by lines 2-2 of FIG. 1;

FIG. 3 is an end elevational view of the two links shown in FIG. 2, taken from the right side of FIG. 2;

FIG. 4 is a rear elevational view of the bottom link in FIG. 2 as well as a front elevational view of the top link in FIG. 2;

FIG. 5 is a front elevational view of the bottom link in FIG. 2 as well as a rear elevational view of the top link in FIG. 2;

FIG. 6 is a fragmentary perspective view on a further enlarged scale of three links of FIG. 1;

FIG. 7 is a top plan view of a single link indicated by lines 7-7 of FIG. 1;

FIG. 8 is a front elevational view thereof;

FIG. 9 is an end elevational view thereof; and

FIG. 10 is a perspective view thereof on a further enlarged scale.

I claim:

The ornamental design for a watch bracelet or similar article, substantially as shown.
